Patented Oct. 20, 1959

186,403

BUTTER MEASURER

Harold Wilson, Liberty, Mo.

Application September 7, 1956, Serial No. 42,870

Term of patent 14 years

(Cl. D52—1)

Fig. 1.

Fig. 2.

Fig. 3.

Fig. 1 is a top plan view of a butter measurer embodying my new design;
Fig. 2 is a bottom plan view of same; and
Fig. 3 is a sectional view of same taken along the line 3—3 of Fig. 2 in the direction of the arrows.

I claim:

The ornamental design for a butter measurer, as shown.
